UNITED STATES PATENT OFFICE

EDDO V. BATES, OF LOWELL, MASSACHUSETTS, ASSIGNOR TO E. V. BATES MACHINE COMPANY, OF LOWELL, MASSACHUSETTS, A CORPORATION OF MASSACHUSETTS

SET OF CARDS WITH FLAT WIRE TUMMER

Application filed August 14, 1930. Serial No. 475,231.

This invention relates to the process known as carding in the manufacture of textile fabrics.

It is substantially an improvement on patent issued to me, Eddo V. Bates on method and apparatus for carding fibrous material, #1,534,564, April 21, 1925.

Carding machines for carding fiber especially of wool are now usually arranged in what are known as sets. A set may be a first breaker and then either a diagonal or scotch feed followed by a second breaker and finisher which may be coupled together or the first and second breaker may be coupled together, than a diagonal or scotch feed and the finisher.

In some cases, a first and second breaker are coupled together, then a diagonal or scotch feed and then an intermediate and finisher coupled together.

In still other cases, there may be three main cylinders connected together by various methods with no intermediate or scotch feed.

This invention has particular reference to what are known as coupled up cards particularly where there are two main cylinders connected by an intermediate doffer or tummer such as shown in the above patent.

I find that by using a tummer preferably of large size with reference to the two main cylinders and connecting them, such tummer being covered with flat wire instead of card clothing, I get better results.

By card clothing, I mean clothing with an elastic or yielding foundation and round wire teeth.

Under flat wire teeth, I include convex wire toothed card clothing, garnett wire with saw teeth, and burr cylinder wire with flat-topped teeth, both known to the trade as metallic tooth wire.

Such metallic tooth wire will not bend nor give, and convex wire teeth will bend or give very little, while the round teeth of card cloth-

ing will yield and are permanently bent out of shape with little difficulty.

Any flat wire tooth is rigid and, if rigidly held, may separate or even break the stock but will not yield.

However, short stock, dirt and grease fall in between the teeth of card clothing and it is necessary to strip the card clothing cylinder quite frequently in order to make it most effective while I find by using flat teeth on certain rolls, they are automatically cleaned and kept clean whereby stripping by hand is almost entirely done away with and the stock is more evenly treated with much fewer bunches.

In application filed August 14, 1930, Ser. No. 475,230, for combination card clothing and flatwire carding machine pending here-with, I have claimed the use of flat wire tooth workers and strippers engaging card clothing main cylinders and in this application I claim to be the first to use a flat wire tummer or doffer between two main cylinders both of card clothing and also the use of a flat wire doffer to clear the second main cylinder.

By forward running, applied to rolls and cylinders, I refer to the direction in which the top moves from the feed end of the card toward the delivery end, or from left to right in the drawing, and by backward running I refer to the opposite direction. By forward pitching, applied to teeth, I refer to the rake, from base to point when at the top of a roll, being toward the delivery end of the card, and by backward pitch I refer to the opposite pitch.

It is believed that the stock is acted upon as indicated graphically by the lines used in the views although this cannot positively be determined.

I believe I am also the first to use various new combinations of card clothing rolls engaging flat wire covered rolls for working the stock and also for stripping and keeping

clear certain rolls which it is desirable should be kept clear of stock.

By keeping such rolls clean, better stock is produced and hand stripping is reduced to a minimum.

5 The drawing showing the various rolls and other parts is substantially diagrammatic. Arrows indicate the direction of rotation and the pitch and various types of teeth, such as card clothing, flat wire and fancy are shown graphically.

10 Fig. 1 is a diagrammatic side elevation of a coupled up set of cards which might be the first and second breaker with any well-known lap feed.

15 Fig. 2 is a diagrammatic side elevation of a coupled up set of cards which might be a second breaker and finisher or an intermediate and finisher, the set being fed by a feed of the scotch or diagonal type and delivering to a tape condenser.

20 Fig. 3 is a diagrammatic side elevation of a coupled up set of cards, which would ordinarily be a first and second breaker, associated with a breast to which stock is delivered by any of the well-known feed devices.

25 In the drawing, in Fig. 1, 1, 1 may be feed rolls which deliver the stock to a lickerin 2 which in turn delivers to a tumbler 3 all these rolls being covered with flat wire.

30 The stock is picked up by the first main cylinder 13 covered with card clothing and is carded by the flat wire covered workers 14 and 15 associated with which are the flat wire strippers 114 and 115.

35 16 is a fancy of any well known type preferably covered with fancy card clothing.

40 17 is a tummer or intermediate doffer shown as of the same size as first and second main cylinders 13 and 19. This tummer is covered with flat wire and turns backward. It is in stripping contact with main cylinder 13 and in carding contact with second main cylinder 19.

45 Preferably I use an angle doffer stripper 50 covered with flat wire below and between 17 and 19 whereby tummer 17 is thoroughly stripped of stock which is delivered onto the second main cylinder 19.

50 On that account at the point 51 carding takes place and while some of the stock continues to cylinder 19, the lumps and parts which stand up on top of the teeth are carried back to another angle stripper 52 which is covered with flat wire and turns backward. This again cleans tummer 17 and returns the stock to the first main cylinder 13 to be again reworked.

55 This leaves the teeth of tummer 17 between the angle stripper 52 and the contact point with cylinder 13 perfectly clean so that tummer 17 picks up substantially all of the stock leaving the teeth of cylinder 13 clean to pick up more stock from tumbler 3.

60 65 Second main cylinder 19 is covered with

card clothing and the stock on it is carded by the flat wire covered workers 20 and 21 associated with which are the flat wire covered strippers 120 and 121.

65 After passing these workers the stock is 70 brushed up by fancy 22 preferably covered with fancy card clothing and is delivered to the doffer 123 which as shown is covered with flat wire. From this doffer, the stock is removed by a comb 24 of the usual type. 75

80 In Fig. 2, the first and second main cylinders 13 and 19 together with their workers 14, 15, 20 and 21, strippers 114, 115, 120, and 121 and fancies 16 and 22 are the same as in Fig. 1 as is also the tummer or intermediate doffer 17.

85 This view shows a second breaker and finisher, or intermediate and finisher coupled together with a feed A shown in diagram. This feed may be of the diagonal or scotch type.

90 In this feed, the stock 40 in the form of a roving is carried between moving rolls 41, 41 and deposited on a traveling apron 42 from which it is taken by feed rolls 44, 44 and delivered to a lickerin 43 and delivered to the first main cylinder 13.

95 The second doffer 23, however, is covered with card clothing and the stock from it is removed by a comb 24 from whence it passes to a tape condenser T of any well known type shown as having the receiving rolls 30 and 31 around which the tapes pass.

100 In Fig. 2 is shown an angle stripper 54 which strips tummer 17 after the stock has been carded between it and second main cylinder 19 so that the flat wire teeth of 17 are always kept clean to receive stock from first main cylinder 13.

105 In Fig. 3, I show the feed as a flat wire breast such as shown in patent to Eddo V. Bates on garnett worker breast for wool cards #1,368,319, February 15, 1921 including feed rolls K and L, lickerin, breast cylinder D, tumbler F, worker C and stripper B.

110 This breast delivers stock to the first main cylinder 63. As shown, all the rolls of the breast except lickerin E, tumbler F and the feed rolls K and L are of flat wire and the teeth of all the flat wire rolls except stripper B pitch forward while all run backward except cylinder D, lickerin E and feed roll K.

115 However, the type of breast and construction may vary.

120 The first main cylinder 63 is covered with flat wire teeth which pitch forward while the cylinder runs forward.

125 Associated with main cylinder 63 is the flat wire covered worker 64 with flat wire covered stripper 164.

130 Fancy 65 has flat wire teeth which pitch backward and runs backward. Fancy stripper 66 has flat wire teeth which pitch backward. It runs backward and takes most of

the stock from fancy 65 and carries it up on the points of the teeth of cylinder 63. Fancy stripper 165 catches any stock which flies back from fancy 65 and replaces it on the main cylinder.

5 Tummer 17 is the same as in the other views being covered with flat wire.

Associated with tummer 17 are the two angle strippers 50 and 67 each covered with flat wire the same as shown in Fig. 1.

10 The second main cylinder 19 is the same as in the other views as is also the fancy 22 while the doffer 123 is covered with flat wire and is cleared by a comb 24 as shown in Fig. 1.

15 The workers 70 and 71 which work or card the stock on second main cylinder 19, instead of being covered with flat wire are covered with card clothing as are also their strippers 170 and 171.

20 In all cases, I prefer to use a tummer or intermediate doffer covered with flat wire the teeth of which pitch forward and which runs backward and which is in carding relation with the second main cylinder.

25 The teeth of the tummer are preferably cleaned by one or two angle strippers before they reach the teeth of the first main cylinder.

The surface speeds of the various rolls expressed in feet per minute may be feed rolls 1, 1, 44, 44; K and L about 20; workers 14, 15, 20, 21, 64, 70 and 71 about 24; strippers 114, 115, 120, 121, 164, 170 and 171 about 300; main cylinders 13, 19, and 63 about 1,000; tummer 17 from 60 to 100; fancies 16, 22 about 1,200; doffer 23 from 50 to 60 and doffers 123 from 60 to 100; angle strippers, 50, 52, 67 and 54 from 60 to 100; lickerin 2, about 200, tumbler 3 about 450; lickerin 43 about 120; breast rolls, stripper B, 30, breast cylinder D, 150, breast worker C, 24, lickerin E, 150 and tumbler F, 450. Fancy 65, 3,000, fancy stripper 66, 1,200 and fancy stripper 165, 300.

I claim:

45 1. The combination in a coupled up set of cards having a plurality of main cylinders; of feeding mechanism for the first main cylinder; with said main cylinder which is covered with card clothing and travels forward; a plurality of sets of stock working rolls engaging said first main cylinder each set including a flat wire covered worker and a flat wire covered stripper; a fancy covered with fancy wire; a flat wire covered tummer adapted to clear the first main cylinder and engaging a second main cylinder; a flat wire covered angle stripper which engages the tummer and a main cylinder; said second main cylinder which is covered with card clothing and travels forward; a plurality of sets of stock working rolls engaging said second main cylinder each set including a flat wire covered worker and a flat wire covered stripper; a fancy; and a doffer adapted to clear the second main cylinder.

50 covered with fancy wire; and a doffer adapted to clear the second main cylinder, said doffer being covered with card clothing and adapted to deliver stock to a tape condenser; together with said tape condenser.

55 2. The combination in a coupled up set of cards having a plurality of main cylinders; of feeding mechanism for the first main cylinder; with said first main cylinder which is covered with card clothing and travels forward; a plurality of sets of stock working rolls engaging said first main cylinder each set including a flat wire covered worker and a flat wire covered stripper; a fancy covered with fancy wire; a flat wire covered tummer adapted to clear the first main cylinder and engaging a second main cylinder; a flat wire covered angle stripper which engages the tummer and a main cylinder; said second main cylinder which is covered with card clothing and travels forward; a plurality of sets of stock working rolls engaging said second main cylinder each set including a flat wire covered worker and a flat wire covered stripper; a fancy; and a flat wire covered doffer adapted to clear the second main cylinder.

60 3. The combination in a coupled up set of cards having a plurality of main cylinders; of feeding mechanism for the first main cylinder; with said main cylinder which is covered with card clothing and travels forward; a plurality of sets of stock working rolls engaging said first main cylinder each set including a flat wire covered worker and a flat wire covered stripper; a fancy; a flat wire covered tummer adapted to clear the first main cylinder and engaging a second main cylinder; an angle stripper which engages the tummer and a main cylinder; said second main cylinder which is covered with card clothing and travels forward; a plurality of sets of stock working rolls engaging said second main cylinder each set including a flat wire covered worker and a flat wire covered stripper; a fancy; and a doffer adapted to clear the second main cylinder.

65 4. The combination in a coupled up set of cards having a plurality of main cylinders; of feeding mechanism for the first main cylinder; with said first main cylinder; a plurality of sets of stock working rolls engaging said first main cylinder; each set including a worker and a stripper; a fancy; a flat wire covered tummer adapted to clear the first main cylinder and engaging a second main cylinder; a flat wire covered angle stripper which engages the tummer and a main cylinder; said second main cylinder which is covered with card clothing; a plurality of sets of stock working rolls engaging said second main cylinder each set including a worker and a stripper; a fancy; and a doffer adapted to clear the second main cylinder.

and a doffer adapted to clear the second main cylinder.

5. The combination in a coupled up set of cards having a plurality of main cylinders; of feeding mechanism for the first main cylinder; with said first main cylinder; a worker and a stripper engaging the first main cylinder; a flat wire covered tummer adapted to clear the first main cylinder and engaging a second main cylinder; a flat wire covered angle stripper which engages the tummer and a main cylinder; said second main cylinder which is covered with card clothing; a worker and a stripper engaging said second main cylinder; and a doffer adapted to clear the second main cylinder.
